(57) **CLAIM**

The ornamental design for a temporary service pole, as shown and described.

DESCRIPTION

FIG. 1 is a perspective view of a temporary service pole, showing my new design; and,

FIG. 2 is a perspective view of an opposite side of the temporary service pole shown in FIG. 1.

The broken line showing of a service box, wires, and attachment means is for illustrative purposes only and forms no part of the claimed design.
